UNITED STATES PATENT OFFICE.

CHARLES C. KESTY, OF WATSONTOWN, PENNSYLVANIA.

BRICK-DIE.

1,138,573.

Specification of Letters Patent.

Patented May 4, 1915.

Application filed June 17, 1914. Serial No. 845,688.

To all whom it may concern:

Be it known that I, CHARLES C. KESTY, a citizen of the United States, residing at Watsontown, in the county of Northumber-

5 land and State of Pennsylvania, have invented certain new and useful Improvements in Brick-Dies; and I do hereby declare the following to be a full, clear, and exact description of the invention, such as 10 will enable others skilled in the art to which it appertains to make and use the same.

This invention relates to plastic block and earthenware apparatus of that class known as die-expressing, and more particularly to 15 perforating and ornamenting dies.

The object of the invention is to provide means for giving one face of the brick or block a wavy or sinuous appearance, while cutting through this face and the opposite 20 face a longitudinal groove. These blocks or bricks are used mostly for paving purposes, in which case they are laid on edge with the sinuous face of one against the plane face of the next, and the sinuous projections 25 space the bricks slightly so as to permit the entrance of the grouting, the latter flowing into the opposite grooves or channels before it sets and thereby holding the bricks or blocks in true alinement. Yet I do not 30 wish to be confined to this use of bricks made in accordance with the invention, because they may be equally well employed in building a wall or other structure, especially 35 as both edges and both ends are plane. Throughout this specification I will speak of the devices as bricks.

The invention is carried out by an apparatus hereinafter described, embodying an upright knife standing across the mouth 40 or outlet of the die, mechanism for rocking the knife and reciprocating it slightly on its own axis and in timed relation to the exit of the column, and means for permitting the knife to move bodily across said mouth, 45 with its bearings if it have any.

In the drawings:—Figure 1 is an elevation of the outlet end of a die provided with this improvement. Fig. 2 is a plan view thereof, showing one means for rocking the 50 knife. Fig. 3 is a horizontal section through the center of the die-mouth on the line 3—3 of Fig. 1, just above the lugs which form the grooves along the sides of the brick. Fig. 4 is a vertical section through one of the bear- ings of the knife spindle, and the support 55 for such bearing. Fig. 5 is a perspective detail of one of the bricks formed by this machine.

I have shown my invention in the drawings as applied to any suitable form of die 60 D whose outlet or mouth M is tapered slightly as shown, and I have not illustrated the means for mixing and expressing the clay. Nor will it be necessary for the purposes of this invention to show the platen 65 onto which the column of clay is delivered by the die-mouth. In these machines as now manufactured and used, said column is of about the size of two bricks standing on edge and face to face, and with a machine 70 of this character there is employed a cross cutting device with mechanism for actuating it at intervals to sever or chop the column into sections whereof each is the length of a brick, this cutter and mechanism being 75 also omitted from the drawings. The purpose of the present invention is to divide the column into two smaller columns or brick-cores, and to make the line of division wavy or sinuous so that one face of the finished 80 bricks will have slight protuberances or waves, and between them depressions or troughs—there being used about three of each to every brick. This I accomplish by mounting an upright knife 1 across the end 85 of the mouth M, the blade portion of the knife being rather thin and not necessarily very wide, and its body above and below said plate being provided with rounded portions or journals 2 which are mounted in 90 boxes 3, the latter in turn being loosely mounted in transversely elongated slots 4 which are formed in supports 5 attached to the mouth M in any suitable manner. However, it is quite possible to omit the boxes 95 and reduce the size of the slots so that the rounded portions of the knife shall be journaled loosely and directly within the supports. I prefer to use the boxes as shown. Above the uppermost bearing the knife is 100 continued into a spindle 6 which carries a lever 7, and the outer end of this lever is connected by a ball-and-socket joint 8 with a pitman rod 9. The remote end of this rod is pivoted on a wrist-pin 10 which projects 105 from a block 11 adjustably mounted in a radial slot 12 in a wheel 13, and held in adjusted position by any suitable means such

as a set screw 14. The wheel is carried by a shaft 15 mounted in bearings 16 on the die D, and this shaft is rotated in synchronism with some moving part of the brick-forming mechanism, as its ejector for instance, the purpose being to impart a rotation to the shaft 15 which will keep pace with the ejection of the brick column.

The knife blade 1 stands in a plane 10 through the center of the die-mouth so that the column issuing therefrom is bisected. As the crank wheel 13 rotates it causes a waving reciprocation of the blade, or in other words a rocking motion on its own axis. As long as the blade stood edge on to the advancing clay it afforded little or no resistance to the ejection of the column, but as soon as it is turned out of its normal plane and even a little to one side, its oblique disposition to the line of advance sets up resistance which tends to move the blade bodily to one side of the mouth, and this movement is permitted by the movement of the boxes within the slots 4. By the time 20 the knife has traveled bodily to one side the crank wheel 13 makes a half rotation and the knife is turned to the opposite oblique position, whereupon it travels back to the other ends of the slots 4. Meanwhile its 25 cutting edge bisects the column of clay on a wavy or sinuous line as will be clear, whereas as the opposite or outer faces of the two brick cores thus produced will be smooth if the corresponding walls of the mouth M are 30 formed with that end in view.

In order to produce longitudinal channels or grooves in both faces of the bricks being made, the knife 1 at about the center of its exposed portion within the mouth is provided on opposite sides with enlargements 35 or lugs 20, and the upright walls of the mouth are provided with similar lugs 21. It may be that the latter lugs at times could be omitted, or they might be provided with 40 mechanism for rendering them adjustable so as to render the grooves or channels in the plane faces of the bricks deeper or shallower. In fact, if no grooves or channels at all were desired the knife could be replaced 45 by another omitting the lugs 20. In order to protect the bearings of the knife and to form smooth portions or paths 22 along that face of the brick which is provided with the sinuous portion 23, lugs 24 may be formed 50 within the mouth M at top and bottom and in alignment with the axis of the knife 1. The size of these lugs regulates the width of the smooth portions 22 on the brick 25, but it will be understood that the lugs 20 55 and 21 cut the grooves 24. The proportions and materials are not important and need not be elaborated. I have found that the clay column being ejected may be moistened with water rather than oil as usual, and 60 bricks are thereby produced which are in

such a high state of perfection that cracks do not appear in them when they are fired, and an extremely small percentage of them fail to pass the test to which such bricks are subjected.

70

What is claimed as new is:—

1. In a brick machine, the combination with the die through whose mouth a clay column is ejected; of an upright knife movably mounted across said mouth, and means for 75 rocking the knife on its own axis.

2. In a brick machine, the combination with the die through whose mouth a clay column is ejected; of supports above and below said mouth and having transverse 80 slots, an upright knife movably mounted in said slots, and means for rocking the knife on its own axis.

3. In a brick machine, the combination with the die through whose mouth a clay column is ejected; of supports above and below said mouth and having transverse slots, journal boxes slidably mounted in said slots, an upright knife rounded above and below 85 its blade and having its rounded portions 90 mounted in said boxes, and means for rocking the knife on its own axis.

4. In a brick machine, the combination with the die through whose mouth a clay column is ejected; of supports above and below said mouth and having transverse slots, journal boxes slidably mounted in said slots, an upright knife rounded above and below 95 its blade and having its rounded portions mounted in said boxes, a lever projecting 100 from the upper end of the knife, and a reciprocating mechanism for said lever connected with a moving part of the column-forming machine.

5. In a brick machine, the combination 105 with the die through whose mouth a clay column is ejected; of supports above and below said mouth and having transverse slots, journal boxes slidably mounted in said slots, an upright knife rounded above and below 110 its blade and having its rounded portions mounted in said boxes, a shaft connected with the column-forming mechanism, a wheel fast on said shaft and having a radial groove, a block adjustably mounted in said groove 115 and carrying a wrist-pin, a lever fast on the upper end of said knife, and connections between said lever and wrist-pin.

6. In a brick machine, the combination 120 with the die through whose mouth a clay column is ejected; of an upright knife standing across said mouth and mounted loosely in bearings above and below it, lugs on the knife blade between said bearings, and means for rocking said knife on its own axis.

125

7. In a brick machine, the combination with the die through whose mouth a clay column is ejected; of an upright knife standing across said mouth and mounted loosely 130 in bearings above and below it, lugs on the

130

knife blade between said bearings, lugs within the end walls of said mouth and opposite those on the blade, and means for rocking said knife on its own axis.

5 8. In a brick machine, the combination with the die through whose mouth a clay column is ejected; of supports above and below said mouth and having transverse slots, an upright knife rounded above and below its blade and having its rounded portions mounted in said slots, a shaft connected with the column-forming mechanism, a crank 25

10 loosely mounted in said bearings and with its blade standing in line with said lugs, and means for rocking the knife on its own axis.

9. In a brick machine, the combination with the die through whose mouth a clay column is ejected; of lugs within said mouth at the center of its top and bottom, bearings carried by the exterior of the mouth, a knife loosely mounted in said bearings and with its blade standing in line with said lugs, lugs 20 on the knife blade about midway between

said lugs in the mouth, and means for rocking the knife on its own axis.

10. In a brick machine, the combination with the die through whose mouth a clay column is ejected; of supports above and below said mouth and having transverse slots, an upright knife rounded above and below its blade and having its rounded portions mounted in said slots, a shaft connected with the column-forming mechanism, a crank 25

20

upper end of said knife, and connections between said lever and the crank of said wheel.

In testimony whereof I affix my signature in presence of two witnesses.

CHARLES C. KESTY.
